UNITED STATES PATENT OFFICE.

JASON H. GREENSTREET, OF INDIANAPOLIS, INDIANA; CHARLES J. GREENSTREET
ADMINISTRATOR OF SAID JASON H. GREENSTREET, DECEASED.

MULTIPLY PAPER.

Application filed December 20, 1919. Serial No. 346,231.

To all whom it may concern:

Be it known that I, JASON H. GREENSTREET, a citizen of the United States, and a resident of Indianapolis, county of Marion, 5 and State of Indiana, have invented a certain new and useful Multiply Paper; and I do hereby declare that the following is a full, clear, and exact description thereof, reference being had to the accompanying drawings, in which like numerals refer to like parts.

The object of this invention is to produce a relatively strong and cheap multiply paper board. Broadly stated, this multiply 15 paper board comprises a plurality of layers, some of which are preliminarily provided with portions displaced from the normal plane of the paper, combined into a single sheet by interposed adhesive material and 20 the whole sheet compressed to firmly crumple the displaced portions before the adhesive material dries.

More specifically the paper board consists of a plurality of sheets of paper superimposed upon each other, the outside sheets 25 preferably being plain and the intermediate sheet or sheets being folded in relatively narrow parallel folds or corrugations so that the folds or corrugations will preferably overlap each other when compressed or crumpled and thus cause a single sheet to have in itself a plurality of layers or thicknesses of paper. Where a plurality of such 30 folded, corrugated or crumpled sheets of paper are employed, they are arranged so that their folds or corrugations will preferably lie crosswise of each other. The sheets constituting the board are coated with adhesive material before they are compressed 35 and dried to form the finished product.

Along with the foregoing is a further 40 feature of the invention which consists in utilizing the adhesive material between various layers or sheets as a layer of material which, when applied thickly, is a rigid stiff layer giving great rigidity, stiffness and strength to the ultimate product. In this 45 connection the folded or corrugated intermediate or filler sheets of paper are preferably saturated with or drawn through a bath of adhesive material, such as silicate of soda, which causes the silicate of soda to fill the spaces, between the different sheets, and in the depressions of the different folds 50 or crumples of the material and thus be

thick enough to form very stiff rigid layers of silicate of soda in the finished product. This enables a very strong, stiff paper board to be made with relatively less paper stock or material because it, or the folds thereof, 60 is supplemented by the adhesive material or silicate of soda, and a sheet of paper folded as hereinafter set forth will, with the adhesive material or silicate of soda, furnish five layers or the equivalent of five layers of 65 paper adhesively and rigidly secured together.

The crumpling or folding of the filler 70 layers and the ultimate association of the sheets, result in a compression or crumpling of the folds or corrugations, and, therefore, in a distortion of the fibres of the paper more or less irregularly in such manner as to increase the strength of the ultimate 75 product, not only against bending and stresses, but also against perforations. This irregular arrangement of the fibres of the crushed paper cooperates with the adhesive material when dry and rigid, to produce the 80 finished product.

A further object of my invention is to provide a board that is stronger than the stock corrugated board by filling the valleys with adhesive material.

Another object of my invention is to provide a strong multiply wrapping and packing paper comprising a sheet of paper made of a plurality of successive folds or corrugations and successively overlapping each other at their edges to form preferably five 85 thicknesses at the point of overlapping and three thicknesses between the overlapping portions of the folds, and adhesive material binds and secures together the five thicknesses at the overlapping of the folds, leaving the three intermediate thicknesses without adhesive material to render the product 90 flexible. The uniting of the overlapping portions of the folds serves to add strength 95 to the paper.

The full nature of the invention will be understood from the accompanying drawings and the following description and claims:

In the drawings, Fig. 1 is a plan view of 105 said new multiply paper board cut away to illustrate the make-up of the product, the folds or crumples being indicated by dotted lines with the layers of adhesive material omitted for clearness. Fig. 2 is a section on 110

the line 2—2 of Fig. 1 and on substantially the same scale. Fig. 3 is a portion of Fig. 2 on a much larger scale. Fig. 4 is a section through a modified form of intermediate 5 or filler sheet and adjacent external sheet, being a sheet of well-known corrugated board arranged crosswise of each other. Fig. 5 is a section through the multiply board made of two sheets of said corrugated paper 10 board cross wise of each other. Fig. 6 is a section through a finished paper or board formed of a corrugated board having a single intermediate corrugated sheet between two outside sheets and the whole compressed. 15 Fig. 7 is a section through a modified form of multiply wrapping paper.

In the drawings there is shown in Fig. 3 a multiply paper board having a lower sheet 10 of plain paper, an upper sheet 11 of plain paper, and two intermediate or filler sheets 20 or layers 12 and 13, respectively, which are folded or corrugated sheets and also thicknesses 14 of adhesive material, which has become dry and hard. The elements 25 constituting the board just described are compressed tightly together in their manufacture so as to produce, when finished, a very strong, hard, stiff board. The folds of the intermediate or filler sheets 12 and 13 30 are relatively narrow folds overlapping each other, and the two sheets 12 and 13 are placed upon each other so that their folds extend preferably transversely of or at right angles to each other.

35 The nature of the invention will be more fully understood from a brief description of the preferred method of making the same. The sheets 12 and 13 are folded, as shown, with their folds partially overlapping each 40 other so that at one point of each fold there are three thicknesses or layers of paper and where they overlap each other, there are five thicknesses or layers of paper. Thus, referring to Fig. 3, the upper layer 121 of a 45 fold is, say $1\frac{1}{8}$ inches wide, and the lower layer 122 of such fold is $\frac{5}{8}$ of an inch wide, and the adjacent folds are made in similar dimensions and, therefore, two folds would overlap $\frac{1}{8}$ of an inch. Hence, at the overlapping portions of said folds, there are five 50 thicknesses of said paper and in the remainder of said folds there are three thicknesses of paper. The intermediate filler sheet 13 is similarly folded. Then said 55 sheets 12 and 13 are drawn through silicate of soda or other adhesive in liquid form so that the adhesive material adheres to all surfaces of said sheets and the folds thereof. As shown in Fig. 3, the two side surfaces of 60 the sheet 12, as a whole, have successive depressions caused by the overlapping edges of the folds and these depressions become filled with the adhesive material 14 so that the adhesive material makes a practically 65 smooth surface on both sides of the sheet

12, entirely enveloping said sheet and filling the spaces between the folds. It is obvious that if the folds of the sheet 12 are not compressed flat, as shown in Figs. 2 and 3, but are somewhat open, they will receive and 70 retain a much greater thickness or layer of adhesive material or silicate of soda, as shown in Fig. 7.

The sheets 12 and 13 thus folded and treated with adhesive material, are placed between the two outer layers 10 and 11, with their folds lying cross wise or at right angles to each other. Then all of the sheets and layers are compressed and the adhesive material allowed to dry. When it is dried, it is obvious that a very stiff and strong multiply board is formed, as it has a very large number of thicknesses of paper and also a considerable number and relatively thick 80 layers of adhesive material. The invention, however, is not limited to any particular thickness of the layers of adhesive material, that being left to the choice of the manufacturer. It can be applied to the sheets 85 of paper or layers in a thin form and with a brush, if desired, or drawn through a tank containing liquid adhesive, as above explained, and the folds of the intermediate sheets may be relatively close together when the adhesive is applied, or be somewhat open, and thus render the layers of adhesive material relatively thicker, so that when dried, 90 said layers will be stiff and hard.

In the preferred manner of manufacture, 100 plain flat paper is fed into a machine to form the intermediate layers 12 and 13. Said layers 12 and 13 are laid together cross-wise and passed through a bath of an adhesive, such as silicate of soda. As they 105 emerge therefrom, they are preferably fed between the top and bottom sheets 10 and 11 and the whole compressed to the thickness desired and dried preferably by passing between heated rollers or any well known 110 means of compressing and drying.

In the modified form in Figs. 4 and 5, there is shown a multiply paper or board formed of two ordinary corrugated paper boards passed through or saturated or coated with silicate of soda or other adhesive material and compressed and dried, as above 115 explained. The two sheets of corrugated board are arranged so that the corrugations extend transversely of each other and when they are compressed, the corrugations are crushed and crumpled down so as to fold and overlap in substantially the same way as in the form shown in Figs. 2 and 3, but without any regularity, as is obvious. This 120 will give to some portions of the intermediate sheet of paper three or more thicknesses, but the fibres will extend in various directions and the adhesive material will be under and over each fold and portion thereof, as 125 in the other form, and when dried, will form 130

dry, rigid layers of adhesive material, which will not only cause the sheets of paper to adhere to each other, but also give stiffness and strength to the the ultimate product.

5. It is observed that in building up this board, the adjacent plys are so arranged that the normal grain of one layer of paper is transverse of the grain of the other layer of paper. Also the various folds and 10 corrugations are vertically compressed or crumpled laterally, and leave depressions for receiving additional thicknesses of adhesive material. It is also noted by the arrangement of the folds of the intermediate 15 sheets of paper, whereby a portion thereof has a thickness of more layers than other portions thereof with intermediate depressions to some extent between them, filled with adhesive material, greater strength, 20 durability and effectiveness of paper board may be obtained without the necessity of having the same thickness in continuous lengths of flat paper for the length of the board. Thus a considerable saving of paper 25 is effected and at the same time a relatively stronger paper board results.

By "multiply" paper or paper board herein is meant paper or paper board including in its make-up one or more sheets of paper folded on itself or corrugated and subsequently compressed and crushed or crumpled. The invention is not necessarily limited to paper or paper board wherein an intermediate sheet is provided with folds 30 or corrugations exactly as herein shown, as said intermediate sheet or sheets may be otherwise formed in the manufacture of the board so that when the same is compressed, portions thereof will fold, crumple 35 down, or overlap other portions thereof and give to portions of said intermediate sheet or sheets a plurality of thicknesses, substantially as above set forth. Nor is the invention necessarily limited to the board substantially as herein set forth which has been 40 compressed.

Fig. 7 illustrates a form of wrapping paper consisting of a single sheet of paper with a succession of folds or corrugations 45 with their successive edges overlapping each other so as to make five thicknesses at the overlapping places and at such places the layers or thicknesses are secured together by adhesive material.

55. This materially strengthens the paper and leaves the portions intermediate the overlapping portions free from adhesive material so as to be flexible.

By "folds" herein is meant overlapping folds substantially as shown in Figs. 2, 3, 5, 6 and 7 thereof.

The invention claimed is:

1. A multiply paper comprising a plurality of layers secured together by adhesive material, one or more intermediate layers be-

ing provided with crushed portions displaced from the normal plane of the paper and overlapping each other and secured together by adhesive material, substantially as set forth. 70

2. A multiply paper, comprising a plurality of layers having the normal grain of one layer arranged transversely to the normal grain of an adjacent layer, and some of the layers provided with crushed portions displaced from the normal plane of the paper or corrugated, and overlapping each other and secured together, the several layers combined into a single sheet by interposed adhesive material. 75 80

3. A multiply paper, comprising a plurality of layers, at least one layer being folded into a multiplicity of overlapping crushed folds and the spaces therein filled and the surfaces covered with adhesive material for uniting the layers and cementifying the multiply paper. 85

4. A multiply paper, comprising a plurality of layers, at least one layer being preliminarily folded into a multiplicity of overlapping folds and associated with an adhesive, the several layers being formed into a single sheet by adhesive and pressure sufficient to firmly compress the overlapping folds. 90 95

5. A multiply paper or paper board including a sheet of paper with successive crushed folds leaving depressions in the surface of said intermediate sheet, a plain flat sheet secured to the sides of said folded corrugated sheet, and adhesive material filling the spaces between the external sheets and adjacent surfaces of the folds of the intermediate sheet. 100

6. A multiply paper or paper board including one or more sheets of paper, each of which sheets is formed with a succession of crushed folds for giving portions of said intermediate sheet a plurality of thicknesses of paper, adhesive material coating the surfaces of said sheet and the folds thereof, and a plain flat sheet of paper. 105 110

7. A multiply paper or paper board comprising external sheets of paper, one or more intermediate sheets of paper between said external sheets of paper, said intermediate sheet or sheets being formed with a succession of crushed folds for giving portions of said intermediate sheet a plurality of thicknesses of paper, and a layer of adhesive material between the external sheets of paper and the said folded intermediate sheet or sheets of paper, substantially as set forth. 115 120

8. A multiply paper or paper board comprising external sheets of paper, a plurality of intermediate sheets of paper between said external sheets of paper, said intermediate sheets being formed with a succession of overlapping folds and said intermediate 125 130

- sheets being arranged so that the folds of one of said sheets will extend transversely of the folds of the adjacent intermediate sheet or sheets, and a layer of adhesive material between the external sheets and the various sheets of paper constituting the multiply paper board the whole being secured tightly together, substantially as set forth.
10. 9. A multiply paper or paper board comprising external sheets of paper, one or more intermediate sheets of paper between said external sheets of paper, said intermediate sheet or sheets being formed with a succession of folds for giving portions of said sheet different thicknesses of paper at different portions thereof, and a layer of adhesive material between the external sheets of paper and the said folded intermediate sheet or sheets of paper, substantially as set forth.
15. 10. A multiply paper or paper board comprising external sheets of paper, one or more intermediate sheets of paper between said external sheets of paper, said intermediate sheet or sheets being formed with a succession of crushed folds, one side of each of said folds being less than twice as wide as the other side of said fold, and said folds overlapping so that portions of each of said intermediate sheet or sheets will provide three thicknesses of paper and other portions five thicknesses of paper, and a layer of adhesive material between the external sheets of paper and the said folded intermediate sheet or sheets of paper the whole being secured tightly together, substantially as set forth.
20. 11. A multiply paper comprising a plurality of interior layers of paper having overlapped portions producing ridges of a greater number of layers than portions between ridges, the ridges of one internal layer lying transversely of the ridges of an adjacent internal layer, facing sheets, adhesive between the internal layers and between the internal layers and the facing sheets, the whole having been firmly compressed to cause substantial adherence between the major portions of adjacent surfaces both of the internal layers and the internal layers and facing sheets.
25. 12. A multiply paper comprising two filler layers preliminarily folded into slightly overlapping substantially parallel pleats and two adjacent layers being placed with the pleats of one lying transversely of the pleats of the other, two facing sheets, and adhesive between the several sheets, the whole being firmly compacted by pressure sufficient to intimately associate the sheets and adhesive substantially throughout the entire area of the product.
30. 13. A multiply paper including one sheet of paper formed with a succession of folds or crumpled corrugations with their adjacent edges overlapping each other for increasing the number of thicknesses of the sheet, and adhesive material securing and uniting together said overlapping portions, the remaining portions of the sheet being free from adhesive material.
35. In witness whereof, I have hereunto affixed my signature.

JASON H. GREENSTREET.

Certificate of Correction.

It is hereby certified that the grantee in Letters Patent No. 1,507,372, granted September 2, 1924, upon the application of Jason H. Greenstreet, of Indianapolis, Indiana, for an improvement in "Multiply Paper," was erroneously described and specified "Charles J. Greenstreet, administrator of the estate of said Jason H. Greenstreet, deceased," whereas said grantee should have been described and specified as *Charles J. Greenstreet, executor of the estate of said Jason H. Greenstreet, deceased*, as shown by the records of assignments in this office; and that the said Letters Patent should be read with this correction therein that the same may conform to the record of the case in the Patent Office.

Signed and sealed this 11th day of November, A. D. 1924.

[SEAL.]

KARL FENNING,
Acting Commissioner of Patents.
